Primary Examiner — Darlington Ly(74) *Attorney, Agent, or Firm* — RatnerPrestia**CLAIM**

The ornamental design for a disposable kit for a dialysis machine, as shown and described.

DESCRIPTION

FIG. 1 is a front elevation view of a disposable kit for a dialysis machine showing our new design;
 FIG. 2 is a front, top, and right side perspective view thereof;
 FIG. 3 is a front elevation view of a disposable kit for a dialysis machine showing our new design in accordance to an alternate embodiment; and,
 FIG. 4 is a front, top, and right side perspective view thereof.
 The broken lines in the drawings illustrate portions of the disposable kit for a dialysis machine that form no part of the claimed design.
